UNITED STATES PATENT OFFICE.

CHARLES H. LEARNED, OF MERIDEN, CONNECTICUT.

DESIGN FOR COFFIN-SCREWS.

Specification forming part of Design No. **11,438**, dated September 30, 1879; application filed June 20, 1879.
[Term of patent 7 years.]

To all whom it may concern:

Be it known that I, CHARLES H. LEARNED, of Meriden, county of New Haven and State of Connecticut, have invented a new Design for Coffin-Screws; and I do declare the following, when taken in connection with the accompanying illustration and letters of reference marked thereon, to be a full, clear, and exact description of the same.

Letter A is a view of a lily-flower in *basso-rilievo*, as represented on one side of head to screw; letters B C, views of leaves in *basso-rilievo*, represented as belonging to the flower; letters D E, views of lily-flower, represented in *basso-rilievo*, on the surface of the plate, one each end. Said plate in shape is oblong. Letters F G H I, views of leaves in *basso-rilievo*, represented as belonging to the lily-flower on each end of the plate.

The invention relates to a design for screws, commonly called "coffin-screws," which are used in securing coffin-covers; and the invention consists in the configuration and ornamentation, as hereinafter described, and as shown in the accompanying illustration.

The head of screw, as seen, letters A B C, consists in the representation in *basso-rilievo* of a lily-flower, with its leaves on each side of the head. The lily-flower, with its leaves in *basso-rilievo*, are represented on each of the two sides of the head of screw.

The plate, of oblong shape, has on its metal

surface the representation of a lily-flower, with its leaves in *basso-rilievo*, on each end, letters D E F G H I, as seen in the accompanying illustration.

The screw passes through the center of the plate, so that the base rests thereon.

The essential feature of the design I regard as the representation in *basso-rilievo* of a lily-flower, with its leaves for thumb-screw on each of the two sides of the head, and of the lily-flower with its leaves represented in *basso-rilievo* on each end of the oblong plate.

The screw may be used with another plate, or the plate with another screw, it only being essential that there be some plate used with the screw or some screw used with the plate.

I claim—

1. The design for coffin-screw, consisting of the representation of a lily-flower, with its leaves in *basso-rilievo*, on the head of the screw, on each of its two sides, as shown in the accompanying illustration.

2. The design for coffin-screw, consisting of the representation of a lily-flower, with its leaves in *basso rilievo*, on each end of the oblong plate, as shown in the accompanying illustration.

CHARLES H. LEARNED.
